CLAIM

The ornamental design for a retainer for a computer mouse, as shown and described.

DESCRIPTION

FIG. 1 is a perspective view of a retainer for a computer mouse showing my new design;

FIG. 2 is a front elevation view thereof on an enlarged scale;

FIG. 3 is a rear elevation view thereof on an enlarged scale;

FIG. 4 is a right side elevation view thereof;

FIG. 5 is a left side elevation view thereof;

FIG. 6 is a top plan view thereof; and

FIG. 7 is a perspective view on a reduced scale showing the design in its environment with a computer, keyboard and mouse in broken lines for illustrative purposes only.

FIG 1

FIG 2

FIG 3

FIG 4**FIG 5**
